Primary Examiner — Mark Goodwin(74) *Attorney, Agent, or Firm* — Rebecca Henkel(57) **CLAIM**

The ornamental design for an agricultural implement tank, substantially as shown and described.

DESCRIPTION

FIG. 1 is a perspective view of an agricultural implement tank, in which the phantom lines illustrate an inductor box assembly, mounting brackets, and a hatch;

FIG. 2 is a top view of the agricultural implement tank; FIG. 3 is a right side elevation view of the agricultural implement tank, the left side elevation view being a mirror image of the left side elevation view being shown;

FIG. 4 is a front elevation view of the agricultural implement tank;

FIG. 5 is a back elevation view of the agricultural implement tank; and,

FIG. 6 is a bottom view of the agricultural implement tank. The broken line showing of an inductor box assembly, mounting brackets, and a hatch in the figures is included for the purpose of illustrating environmental structure only and forms no part of the claimed design.
